UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

DISTRIBUTING MECHANISM OF TYPOGRAPHICAL COMPOSING-MACHINES.

1,222,018.

Specification of Letters Patent. Patented Apr. 10, 1917.

Application filed April 14, 1915. Serial No. 21,421.

To all whom it may concern:

Be it known that I, CARL MUEHLEISEN, a citizen of the United States of America, residing at Chausseestrasse 23, Berlin, N. 4, in the Empire of Germany, have invented new and useful Improvements in the Distributing Mechanism of Typographical Composing-Machines, of which the following is a specification.

10 This invention relates to typographical composing and distributing machines such as those known commercially under the trade mark "Linotype". Ordinarily in such machines, the so-called sorts matrices which are 15 not stored in the magazine but are added by hand to the line of matrices in course of composition, are, during the subsequent distribution of the said line, conveyed along the whole length of the distributor bar, and 20 are permitted to drop from the end thereof into a chute by which they are conveyed to a special receptacle, known as a pi-bowl, situated near the keyboard of the machine, so that the said sorts matrices are within convenient 25 reach of the operator when required for further use. A similar method of distributing sorts matrices is employed in machines which are provided with a plurality of magazines and distributors, wherein the 30 line of matrices to be distributed is first presented to a preliminary or font-distributor. The font-distributor effects the separation of the ordinary matrices according to the magazines to which they belong, and 35 delivers them into chutes by which they are conveyed to the distributors appropriate to the respective magazines. The sorts matrices, however, are conveyed along the whole length of the ribbed bar in the font-distrib- 40 utor and are only released from it at the point where the matrix-supporting ribs are discontinued, above the last chute in the series, by which chute they are conveyed to the distributor of the respective magazine to 45 be dealt with in the same manner as in the above-mentioned case of a single distributor.

It will be seen that this method of distributing sorts matrices must result in unnecessary wear of their teeth and of the ribs 50 on the particular distributor bar along which all such matrices have to travel after leaving the font-distributor. In order to avoid this unnecessary wear, means have been provided for conveying sorts matrices 55 beyond the last chute in the font-distribu-

ter and delivering them to a special chute which guides them to the pi-bowl, but such special chute has necessarily been long and bent, with the result that the matrices could not pass freely therethrough.

According to the present invention, the just-mentioned disadvantages connected with the distribution of sorts matrices are eliminated by providing improved means for the conveyance of such matrices from the font-distributor to the pi-bowl.

The accompanying drawings show diagrammatically sufficient of a machine provided with four magazines to illustrate the application thereto of a constructional form of the invention,

Figure 1 being a front elevation thereof, and

Fig. 2 a sectional elevation, as seen from the right-hand side of Fig. 1, and on larger scale than that to which the said figure is drawn.

The ordinary matrices are composed in well-known manner from the magazines 1, a particular font of such matrices being stored in each magazine, and after the desired cast has been taken from the composed matrices, they are presented to the font-distributor 2 which separates them according to font and delivers them, through the chutes 3 to the distributors 4 by which they are returned to the proper channels of the particular magazine appropriate to the fonts to which they belong.

The so-called sorts matrices, which are not stored in the magazines 1, but are added by hand to the line in course of composition, are also presented, along with the ordinary matrices, to the font-distributor 2, but, instead of being delivered thereby to one or other of the chutes 3, they are carried over those chutes to the end of the font-distributor and delivered to a special chute 5. According to the present invention the sorts matrices are guided by the chute 5 onto an endless conveyer belt 6, by which they are conveyed in the direction of the arrow in Fig. 1 and discharged, through a funnel 7 into a chute 8 down which they drop directly into the pi-bowl 9. The course of the sorts matrices from the font-distributor to the pi-bowl is clearly indicated in Fig. 1 by the matrices 10, 11, 12 and 13, which are shown in respectively different parts of their travel.

The conveyer belt 6 passes around constantly rotating pulleys 14, 15, either of which may be driven in any convenient manner; for example, as indicated in Fig. 2, the pulley 14 may be driven by a half-crossed belt 16 passing over two pulleys 17, 18, the former attached to the shaft of one of the font-distributer screws and the latter fast to the spindle of the pulley 14.

- 10 It will be understood, of course, that my invention will also be useful in the handling of matrices of improper font, or reversed matrices, or matrices without distinguishing combinations or mutilated ones, which 15 may have found their way into the composed line and which would be rejected by the usual font selectors. Such matrices in the present construction would also be delivered onto the conveyer belt and transported to the pi-bowl.

Having described my invention I declare that what I claim and desire to secure by Letters Patent is:—

1. In a typographical machine, the combination with a primary distributing mechanism adapted to separate matrices according to font, and receptacles for receiving the matrices separated by the primary mechanism, of a sorts-disposing mechanism adapted to 25 dispose of matrices undistributed by the primary mechanism and including an independent receptacle located at a point distant 30

from the distributing mechanism, and means for conveying the matrices to said distant receptacle comprising a conveyer 35 and a chute interposed between the conveyer and the receptacle to receive the matrices from the conveyer and discharge them into the independent receptacle.

2. In a typographical machine, the combination with a primary distributing mechanism adapted to separate matrices according to font, receptacles for receiving the matrices separated by the primary mechanism, of a sorts-disposing mechanism adapted 40 to distribute matrices undistributed by the primary mechanism and including an independent receptacle located at a point distant from the distributing mechanism, and means for conveying the matrices to said distant receptacle including a conveyer traveling in an approximately horizontal plane, and a vertically disposed chute interposed between the conveyer and the receptacle to receive the matrices from the conveyer and discharge them into the independent receptacle.

In witness whereof I have hereunto set my hand in the presence of two witnesses.

CARL MUEHLEISEN.
